UNITED STATES PATENT OFFICE.

HERBERT CHAMPION HARRISON, OF LOCKPORT, NEW YORK.

RADIATOR.

1,005,028.

Specification of Letters Patent.

Patented Oct. 3, 1911.

Application filed January 16, 1911. Serial No. 602,956.

To all whom it may concern:

Be it known that I, HERBERT C. HARRISON, a citizen of the United States, residing at Lockport, in the county of Niagara and 5 State of New York, have invented certain new and useful Improvements in Radiators; and I do hereby declare the following to be a full, clear, and exact description of the invention, such as will enable others skilled 10 in the art to which it appertains to make and use the same.

This invention relates to radiators especially adapted for use upon automobiles and other vehicles, and has for its object to produce a more efficient and a simpler structure than those heretofore produced for this purpose.

To these ends the invention consists in the novel details of construction and combinations of parts more fully hereinafter disclosed and particularly pointed out in the claims.

Referring to the accompanying drawings forming a part of this specification in which like numerals designate like parts in all the views, Figure 1 is an elevational view of a radiator made in accordance with my invention; Fig. 2 is an enlarged detail sectional view of a portion of the parts shown in 20 Fig. 1; Fig. 3 is a detail sectional view of a slightly modified form of construction; Fig. 4 is a plan view of one of the separating plates showing by dotted lines the places at which said plates are bent at the corners 30 of the radiator cells; Fig. 5 is a plan view of a portion of a separator plate with a plurality of tubes in place; Fig. 6 is a detail sectional view of a still further modified form of construction; and, Fig. 7 is a plan 40 view of a portion of a separator plate of the construction shown in Fig. 6.

1 indicates any suitable outer casing provided with an upper chamber 2 adapted to receive a cooling fluid such as water, and 45 also provided with a lower chamber 3 from which said cooling fluid is withdrawn from the casing 1. The said casing 1 is also provided with an enlarged opening 4 through which air or other cooling medium passes, 50 and which serves to expose the cells of the radiator.

In the casing 1 is located a plurality of

tubes 5 through which the fluid to be cooled passes, and these tubes are separated by plates 6, in a manner well known. Further, 55 the general shape of the radiator cellular structure is polygonal as indicated, and therefore the upper separating plate 7 generally has to have differently spaced perforations at the corners, such as 8, than it 60 has at the sides or top, such as 9. That is to say, in order for the tubes 5 to properly pass through said plate 7 at a corner, it has been heretofore thought necessary to make the perforations somewhat larger at the 65 corners than those perforations which occur on the top or side of the plate. In this way the angle at which the plate strikes the tubes was allowed for, and it was further found that the perforations had to be spaced somewhat farther apart than was the case at the 70 sides or top of the plate. In manufacturing radiators however, on a large scale, it is a considerable item of expense to perforate the plate by one set of dies for the tops and 75 sides and to then perforate the plate by another set of dies differently spaced for the corners, for this not only involves two operations, but it also involves the extra cost of the second set of dies, as well as a considerable loss of time. According to my invention however, I use the same dies throughout, and make the perforations of the same size throughout the plate. The only change I make for the corners is, I 80 space the dies for these portions of the plate differently from the dies which perforate the rest of the plate. That is to say, as plainly shown in Fig. 4, I provided a series of perforations 10 equally spaced, for the 85 top and I also provided another series of perforations 11 which may be spaced twice as far apart as are the perforations 10 for a cover. This is easily accomplished either by rendering alternate cutting dies inoperative or by omitting them altogether for those portions of the plate which occupy the corners of the cellular structure. I next bend the plate into steps along the lines 12 as best illustrated in Fig. 2, when the tubes 13 at the corners will pass through the perforations 11 at right angles to the plate 7, precisely as do the tubes 5 at the ends pass through the perforations 10. In this way

the perforations 11 are made without any extra expense whatever, and they are of uniform size throughout the plate.

Of course all of the tubes are suitably attached to the plates as by drops of solder 14 in order to make water-tight joints, and an exceedingly efficient and inexpensive structure results. The construction is further lessened in cost by the fact that said tubes 5 as best shown in Fig. 5, are preferably made out of a single strip of material which is first corrugated and then bent back upon itself as at 14, to form a series of tubes 5. The ends 15 of the strip are next suitably secured together as by rolling or bending over as shown. In order that the cooling air may act more efficiently, one series of tubes 5 may be staggered in relation to the next series as illustrated, thus producing a zig zag passage 16, which forces the air to ballot back and forth from one series of tubes to the other in its passage through the radiator. The staggering of the said tubes 5 requires that one set of tubes should have a longer folded tongue 17 than is the tongue 14 of the contiguous set and of course the separating plates such as 7 are provided with alternate, corresponding, elongated slots 18, as illustrated in Fig. 4.

30 In the modified form of construction shown in Fig. 3 the separating plates 6 are provided with numerous perforations 20 through which air may pass from one passage 16 to a contiguous passage, and therefore be permitted to more freely circulate up and down through the cellular structure.

In the still further modified form of structure shown in Fig. 6 the corrugations of the separate plates are made hexagonal in shape, 40 and the walls of the cells thus formed are freely perforated as at 21 in order that a very free circulation of air may take place throughout the cellular structure. These numerous perforations 21 accordingly cause 45 the air to be broken up and thrown into eddies as it passes through the radiator and thereby it forces a more complete contact between every particle of air and the tubes to be cooled than would be the case if the air 50 simply passed through individual passages 25. In all cases it will be observed that the structures of the same radiator elements are duplicates of each other and therefore the parts may be made at a minimum of cost.

55 What I claim is:

1. In an angular radiator structure the combination of a separator plate having perforated straight and bent portions to conform to the shape of said structure, the distance between the perforations in the bent portions being a plurality of times greater than the distance between the perforations in the straight portion; and a plurality of

tubes of uniform size passing through each set of perforations and making the same angle with said plate, substantially as described. 65

2. In a radiator structure provided with top and corner portions, the combination of a separator plate provided with equally spaced perforations throughout said top portions and with equally spaced additional perforations of the same size as said first mentioned perforations throughout said corner portions; and a plurality of tubes of 75 uniform size passing through each set of perforations at the same angle to said plate, substantially as described.

3. In a radiator structure having top and corner portions and a chamber above said portions, the combination of a separator plate extending over said top and corner portions provided with a series of perforations of equal size through each of said portions, the perforations associated with the 80 corner portions being spaced differently from those associated with the top portion; and a plurality of tubes of uniform size 85 passing through said perforations and making the same angle with said plate, substantially as described. 90

4. In a radiator structure provided with corners, the combination of a plurality of perforated separator plates; a plurality of tubes passing through the perforations and forming therewith a cellular structure provided with air passages, said plates also having additional perforations permitting the air to pass from one passage into a contiguous passage; and an outer separator 100 plate having straight and bent portions provided with perforations through which said tubes pass at the same angle to said plate, the perforations in the bent portions being spaced twice as far apart as the perforations 105 in the straight portions, substantially as described.

5. In a radiator structure provided with corners, the combination of a plurality of perforated separator plates; a plurality of tubes passing through the perforations, and forming therewith a cellular structure provided with air passages, said plates also having additional perforations permitting the air to pass from one passage into a contiguous passage; and an outer separator plate bent at an angle to itself to form steps, 110 extending over said corners and provided with perforations of the same size as said first mentioned perforations through which 115 said tubes also pass, substantially as described.

6. In a radiator structure a separator plate provided with a plurality of oblong perforations equally spaced throughout one 120 portion; throughout another portion pro- 125

vided with a plurality of perforations of the same size as said first mentioned perforations, but spaced farther apart and said plate bent into steps causing said latter perforations to be located in planes parallel to said first mentioned perforations, substantially as described.

In testimony whereof, I affix my signature, in presence of two witnesses.

HERBERT CHAMPION HARRISON.
